UNITED STATES PATENT OFFICE.

LÉON EMILE RÉMONDY, OF RUEIL, FRANCE.

FUSE BODY FOR PROJECTILE FUSES.

Application filed September 26, 1924. Serial No. 740,120.

To all whom it may concern:

Be it known that I, LÉON EMILE RÉMONDY, a citizen of the Republic of France, resident of Rueil, France, have invented new 5 and useful Improvements in Fuse Bodies for Projectile Fuses, which are fully set forth in the following specification.

The present invention relates to the construction of fuse bodies for projectile fuses.

10 In conformity to the invention, it is possible to construct a fuse body in an entirely economical and judicious manner, by the use of materials, of which some are strong, and others of less strength, suitably arranged 15 in one block. The new fuse body finds its application particularly in modern fuses which are extremely sensitive and of instantaneous operation. In these fuses it is above all important to consider the 20 resistance of the parts of the fuse body to the forces to which they will be subjected upon the firing of the shot, since the deformation under the shock of impact can in no way affect the operation, the latter taking place 25 upon the lightest contact and being ensured before a deformation by penetration can have been produced.

For these modern fuses, the body of the fuse is, according to the invention, comprised of two members, connected together 30 by one being cast on the other in a mould, and arranged in a special manner; one, made of stronger metal, comprises an exposed back part which acts as support for 35 the detonator, and may, for this purpose, carry a screw thread or be worked in any other suitable manner, while the front part of this member acts as framework for the front part of the fuse body in which it 40 hooks and is embedded; this front part, in which is placed the firing mechanism, may be made of a weaker metal, since it is reinforced, at the points which are weakest when the shot is fired, by its framework provided 45 by the detonator which is embedded in it.

Two forms of construction of the invention are illustrated, by way of example, in the accompanying drawing, in longitudinal sectional elevation along the axis of the fuse body.

50 In conformity to the invention, the fuse body is constituted by the joining together in the mould, of two members:

55 1. A fuse body proper A, the inside and outside profile of which varies according to the type of fuse, and which holds, in the

usual manner, the mechanism, and, if desired, the various safety devices. The body A may be made of a relatively weak material, for example of aluminium or aluminium alloy, and has the double advantage of having a low cost price and offering facilities for casting which reduce the costs of manufacture.

2. A detonator carrier B—B¹ made of a stronger material, such as brass for example, comprising an exposed back part B, which may be screw threaded or worked in any other suitable manner so as to be adapted for receiving at the lower end the detonator or a part on the latter. The front part of this stronger member is embedded in the body of the fuse proper A and serves as a reinforcing framework for the latter.

It is understood that the shape of the detonator carrying framework B¹—B may vary considerably, the conditions it must fulfill being, on the one hand, of serving as attachment by its outer exposed end B, during assembly, for the detonator or a part of it, and on the other hand, of embedding itself by its front part, in the mould, in the body of the fuse proper, for which it forms a framework and hooks itself as best possible into the weaker material, reinforcing the latter at the points which offer least resistance to the forces to which the body of the fuse is subjected upon the firing of the shot.

One of the most simple and expedient forms of construction of the invention, in practice, will be that illustrated in the accompanying drawing, in which the detonator carrying framework is constituted by a tube, expanded at its upper end b' and thus reinforcing above all the back part of the body A, in the neighborhood of the threads a by which the body is screwed into the nose of the projectile, as well as the part a' where the head of the body A joins on to the extension towards the back part. Holes b² may be made in the framework, as shown in Fig. 1, to allow the passage of the weaker metal in the mould. Instead of holes, corrugations may be formed in the part of the detonator carrier which forms the framework, as shown in Fig. 2, or any other form may be employed to facilitate the anchorage in the body of the fuse proper. In the example shown in Fig. 1, the exposed part B of the detonator carrying framework is screwed internally.

As shown in Fig. 2, the framework may be screwed externally, and the tail of the fuse body proper A extends inside the framework B.

Having now particularly described and ascertained the nature of my said invention and in what manner the same is to be performed, I declare that what I claim is:

1. A shell fuse body comprising an enlarged head portion of comparatively weak cast metal and having a reduced tubular rear extension and a tubular member of stronger metal embedded in said reduced rear extension and projecting rearward therefrom.

2. A shell fuse body comprising a head portion of comparatively weak cast metal

and a tubular reinforcement of stronger metal embedded in a reduced tubular rear extension of said head portion, and means for securing a detonator to the projecting rear end of said reinforcement.

3. A shell fuse body comprising a head portion of comparatively weak cast metal and a tubular reinforcement of stronger metal embedded in said tubular rear extension of said head portion, with its forward end flared outward, and means restraining the two members against relative longitudinal movement.

In testimony whereof I have signed this specification.

LÉON EMILE RÉMONDY.
